UNITED STATES PATENT OFFICE.

ROBERT HELD, OF RANDOLPH, MISSOURI.

OIL-GRAVE.

No. 882,634.

Specification of Letters Patent. Patented March 24, 1908.

Application filed December 2, 1907. Serial No. 404,791.

To all whom it may concern:

Be it known that I, ROBERT HELD, a citizen of the United States, residing at Randolph, in the county of Clay and State of 5 Missouri, have invented certain new and useful Improvements in Oil-Grates, of which the following is a full, clear, and exact description, reference being had to the accompanying drawings, forming a part hereof.

10. My invention has relation to improvements in oil grates; and it consists in the novel construction of grate more fully set forth in the specification and pointed out in the claims.

In the drawings, Figure 1 is a longitudinal 15 section of my grate on the line 1—1 of Fig. 2, showing the same applied to a locomotive boiler; Fig. 2 is a vertical transverse section on the line 2—2 of Fig. 1; Fig. 3 is a sectional detail of the check-valve interposed 20 between the supply tank and the burners; and Fig. 4 is a sectional detail showing the manner of supporting the burner pipes in position.

The object of the present invention is to 25 construct a vapor burning grate which will take the place of the prevailing grate constructions utilizing solid fuel such as coal, wood, coke, and the like, whereby not only economy in fuel results since the feeding of 30 the latter can be perfectly controlled, but the nuisance of smoke and dirt will be entirely eliminated; and while herein specifically shown in connection with a locomotive boiler, it is to be understood that I do not 35 limit its application thereto, but may employ the invention with any type of boiler whatsoever.

The advantages of the invention will be 40 better apparent from a detailed description thereof which is as follows:

Referring to the drawings, B, represents in dotted outline a conventional type of locomotive boiler. Located at any convenient place on the engine is an oil supply tank T, 45 from which leads a supply or feed-pipe a, said pipe being provided with a check-valve V preferably of the gate type as shown in Fig. 3, and with a feed valve V' of any well known form of construction, that here shown 50 being a prevailing type known to the trade. The check-valve V arrests and prevents any back-pressure into the tank T.

The feed-pipe a communicates with a header H, of U-shaped form located at the

front end of the fire-box chamber of the boiler, 55 said header being provided with a series of burner pipes p closed at their free ends which extend rearwardly to the back of the fire box, the pipes p forming collectively a construction comparable to a grate. The 60 grate thus formed is provided with nozzles or burner tips b distributed along the inner faces of the pipes p, the several tips pointing inwardly into the chamber of the fire box. The grate formed in the manner aforesaid 65 extends not only along the bottom of the fire-box but substantially half-way up along the sides thereof, so that the flames or jets issue along three walls, flowing toward the center and thence rearwardly through the 70 fire tubes of the boiler as shown by the arrows in Fig. 1. The pipes p are supported on saddles D cast preferably in the form shown, the saddles being provided with depressions by which the individual pipes p of 75 the grate are received (Fig. 4) so that no displacement of the pipes is possible and a rigid and yet a light construction is the result.

The size and intensity of the flame jets is controlled by the rate of discharge of the oil 80 or hydrocarbon past the valve V', which rate can of course be regulated with the greatest nicety.

Having described my invention what I 85 claim is:

A vapor-burning grate for locomotive boilers comprising a hollow terminal U-shaped header disposed in a vertical plane at the front of the fire-box, a series of rearwardly extending burner pipes communicating 90 with the interior of the header and collectively forming the bottom and sides of the grate, and having peripherally disposed nozzles directed toward the inside of the fire box, suitable saddles for supporting the several 95 pipes, said saddles being provided with depressions for receiving the individual pipes, a source of oil supply, and suitable check and supply valves interposed between the source 100 of supply and the header, substantially as set forth.

In testimony whereof I affix my signature, in presence of two witnesses.

ROBERT HELD.
